UNITED STATES PATENT OFFICE.

CHARLES E. FOGARTY, OF SAN FRANCISCO, CALIFORNIA.

CAN-SORTING MACHINE.

1,158,669.

Specification of Letters Patent.

Patented Nov. 2, 1915.

Application filed February 10, 1915. Serial No. 7,444.

To all whom it may concern:

Be it known that I, CHARLES E. FOGARTY, a citizen of the United States, residing at San Francisco, in the county of San Francisco and State of California, have invented new and useful Improvements in Can-Sorting Machines, of which the following is a specification.

The object of the present invention is to provide means for sorting out filled cans of light weight from full weight cans.

In the accompanying drawing, Figure 1 is a front view of the machine, certain of the cans being omitted for clearness; Fig. 2 is a similar rear view of the machine; Fig. 3 is a plan view thereof; Fig. 4 is a broken horizontal section on the line 4—4 of Fig. 1; Fig. 5 is a vertical section on the line 5—5 of Fig. 4; Fig. 6 is a plan view of the feed table; Fig. 7 is an end view thereof; Fig. 8 is a plan view of a weighing pan; Fig. 9 is a side view thereof.

Referring to the drawing, 1 indicates the main frame or casting of the machine, to which is secured by bolts 2 a feed table 3, which, at the front edge, is formed with a low wall 4 to guide the cans on the table. To the rear end of the feed table is secured by bolts 6 a standard 7, from the rear end of the top of which extends a guide 8, immediately over, and spaced from, the rear margin of the table.

9 indicates a standard, forming part of the main frame, and carrying journal boxes 35 11 in which rotates a horizontal main shaft 12, carrying a driving pulley 13, and having secured thereto a miter gear 14, which meshes with a miter gear 16 keyed to a vertical shaft 17 stepped in a bearing in the frame of the machine, extending through an upper portion 18 of said frame, and carrying at its upper end a crank 19. Rotatably mounted on said upper portion 18 are two other cranks 21 of equal length with the shaft 19, and to the free ends of the three cranks 19 and 21 is pivoted a link 22, formed integral with which is a standard 23, from the top of which extends in a longitudinal direction between said table and the guide 8 50 a pusher plate 24, having three arms 26 extending therefrom in a transverse direction, said plate being concave or rounded between said arms. With each revolution of the crank 19, the operator places a can on the rear end of the table at the time that the

pusher plate is in its most advanced position, and, with each succeeding revolution thereof, an arm is withdrawn from the front of the can and passed to its rear, and then the can is pushed forward on the feed table 60 a distance equal to that between the arms.

The feed table 3 is formed, near its forward end, with a wide opening 27 through its sides, below its top, and the top of the feed table is cut through above said opening to form a narrow passage 28, in the form of an arc of a circle described about a shaft 29 as center.

Formed integral with the miter gear 16 is a gear wheel 31 which meshes with an idle gear wheel 32 rotatable about a vertical shaft 33 having its bearings in the frame, and formed integral with said latter gear wheel, is a mutilated collar 34 around the shaft 33 and a wrist pin 36 carrying a roller 37. Said roller is adapted to engage any one of a number, here shown as eight, of radially extending recesses 38 formed in the edge of a wheel 39, keyed to the shaft 29, to impart rotation to said shaft 29, and the collar is adapted to engage an adjacent one of a corresponding number of cavities 41 intervening between said recesses to arrest the rotation of the wheel, the parts 37, 38, 34, 41 forming a Geneva movement. Above the frame a turret 42 is secured to the shaft 29, to which turret is thus imparted an intermittent rotary movement. Extending upwardly from said turret are eight pairs of standards 43, each having at its upper ends 90 bearings for the downwardly directed knife edges of trunnions 44 extending from opposite ends of a bar 46, from which extends, transversely thereof, or in a radial direction of the turret, scale beams 47. At its inner end each beam carries a weight 48 and at its outer end a bar 49, having at its ends trunnions 51, having upwardly directed knife edges which engage recesses in a frame 52, to which are attached the upper ends of hanger bars 53, which depend through holes in the turret, and are attached at their lower ends to a pan 54, best shown in Figs. 8 and 9.

Each pan in succession, in the intermittent rotary movement of the turret, is caused to engage the downwardly inclined face of a wedge 56, formed on the inner portion of the feed table, which wedge forces the pan downward, so that it passes into the opening 110

27 in the feed table and is brought to rest therein, the hanger bars depending through the passage 28 in the top of the feed table. While the turret is at rest in this position, 5 a cam is pushed by the pusher plate on to the inner end of the feed table, extending about equally on both sides of the passage 28 through the top of the feed table, and the cylindrical side of the can is received within 10 one of the eight semi-cylindrical cavities 40 in the turret, each cavity having an enlarged upper portion 51' to receive the projecting flange of the top of the can. At the next movement of the turret, the pan, being 15 no longer under the depressing action of the wedge, rises up under the feed table, and to prevent the necessity of permitting the can dropping on leaving the table, the passage 27 is enlarged at its forward end on the inner side, as shown at 58. Four upstanding 20 lugs or standards center the can, two of these lugs 59 being on the inner side of the pan next the turret, and two others 61 being almost diametrically opposite to each other 25 near to the line between the hangers. The can is held up by the table and the turret until the rearmost lug 61 has passed from underneath the top of the table and has risen through the enlarged portion 58 of the passage 28 in said top, so that the can is supported by the pan before it has left the edge 30 of the table.

The gear wheel 32 meshes with a gear wheel 62 loose on the shaft 29, and formed 35 integral with a cam wheel 63 having therein an inner cam groove 64, and an outer cam groove 66. In said cam groove travel rollers 67, 68, on pins secured to, and depending from, slide pieces 69, 71, extending at right 40 angles to one another and formed at their outer ends with knuckles 72, 73, which carry pins passing through slots in the ends of short arms of levers 74, 76, pivoted at 77, 78, on the frame of the machine. The inner 45 ends of said slide pieces are formed with slots 79, 81, having rounded ends, which slots engage a collar 82, which connects the gear wheel 62 with the cam wheel 63. The diameters of all the gear wheels 31, 32, 62, 50 are the same, from which it results that each slide piece makes a complete reciprocation with each advance of the can. The upper ends of said levers 74, 76 have slotted pivotal 55 engagements with slides 83, 84, guided in guides 85, 86, and which carry pushers 87, 88. The pusher 88, diametrically opposite to the feed table, is lower than the pusher 87 which is at an angular distance of three-quarters of a revolution therefrom. When a 60 full-weight can arrives at the pusher 88, the pan will have been depressed to such a depth that the pusher 88 in its outward movement of reciprocation, engages the can and pushes it from the pan. But when a light weight 65 can arrives in this position, the pan being at

a higher level, the pusher 88 in its outward movement travels underneath the can and in a groove 89 in the pan. When the light weight can has traveled another quarter of a revolution, it is engaged by the pusher 87, 70 which operates at a higher level than the pusher 88 and then pushes it from the pan.

Thus the machine sorts the full weight and light weight cans.

The provision of self-centering means 75 upon the pan, namely, the lugs 59 and 61 concave on their inner sides, I regard as an important feature of my invention for the reason that thereby the can is automatically placed upon the pan in the position in which 80 it will hang uniformly from the scale beam.

I claim:—

1. The combination of a pan having a surface for supporting a can and a groove below said can-supporting surface, means 85 whereby the level of the can so carried is dependent upon its weight, a pusher, and means for moving said pusher in said groove beneath said can when the can is at the higher level.

2. The combination of a pan having a surface for supporting a can and a groove below said can-supporting surface, means whereby the level of the can so carried is dependent upon its weight, two pushers, one 95 higher than the other, and means for moving the lower pusher in the groove beneath the can when the can is at the higher level.

3. The combination of a vertical shaft, a plurality of weighing devices supported by 100 said shaft, pans depending from the weighing devices, means for feeding cans on to said pans in succession, means for imparting an intermittent motion to the shaft alternately with the forward movement of 105 said feeding means, two pushers, one higher than the other, and means for imparting a reciprocating movement to said pushers across the path of the pans in radial directions making an angle with each other, the 110 movement of reciprocation being timed to take place when the pans are at rest, each pan being arranged to support a light-weight can above the lower pusher.

4. The combination of a vertical shaft, a 115 turret secured thereto having in its edge a plurality of cavities, a corresponding plurality of scale beams mounted upon the turret, a weight carried upon the inner end of each scale beam, pans depending from the 120 outer ends of the scale beams, means for feeding cans on to said pans in succession, means for imparting an intermittent motion to the turret alternately with the forward movement of said feeding means, two pushers, one higher than the other, and means 125 for imparting a reciprocating movement to said pushers across the path of the pans in radial directions making an angle with each other, the movement of reciprocation being 130

timed to take place when the pans are at rest, each pan being arranged to support a light weight can above the lower pusher.

5. The combination of a feed table formed, near its forward end, with a wide opening through its side below its top, and its top being formed, above said opening, with a narrow passage therethrough, means for advancing cans thereon, a vertical shaft, a turret secured thereto having in its edge a plurality of cavities, a corresponding plurality of radially extending scale beams mounted upon the turret, a weight carried upon the inner end of each scale beam, pans depending from the outer ends of the scale beams, said turret being arranged relatively to the feed table so that the feed table extends across the path of each pan, means for imparting an intermittent motion to the turret alternately with the forward movement of said advancing means, means for depressing each pan when it arrives at the feed table so that the pan can pass into the opening therein, the pan having a plurality of standards to support a can thereon, said passage being enlarged at the forward end to permit the rearmost standard to move upwardly therethrough while the can is upheld by the feed table, two pushers, one higher than the other, means for imparting a reciprocating movement to said pushers across the path of the pans in radial directions making an angle with each other, the movement of reciprocation being timed to take place when the pans are at rest, each pan being arranged to support a light weight can above the lower pusher.

6. The combination of a feed table, formed, near its forward end, with a wide opening through its side below its top, and its top being formed, above said opening, with a narrow passage therethrough, means for advancing cans thereon, a vertical shaft, a turret secured thereto having in its edge

a plurality of cavities, a corresponding plurality of scale beams mounted upon the turret, a weight carried upon the inner end of each scale beam, pans depending from the outer ends of the scale beams, said turret being arranged relatively to the feed table so that the feed table extends across the path of each pan, means for imparting an intermittent motion to the turret alternately with the forward movement of said advancing means, means for depressing each pan when it arrives at the feed table so that the pan can pass into the opening therein, the pan having a plurality of standards to support a can thereon, said passage being enlarged at the forward end to permit the rearmost standard to move upwardly therethrough while the can is upheld by the feed table, two pushers, one higher than the other, means for imparting a reciprocating movement to said pushers across the path of the pans in radial directions making an angle with each other, the movement of reciprocation being timed to take place when the pans are at rest, each pan being arranged to support a light weight can above the lower pusher, said lower pusher being arranged to impinge upon a full weight can at a lower level and push it from the pan, the higher pusher being arranged to impinge upon the light-weight can at the higher level and push it from the pan.

In testimony whereof I have hereunto set my hand in the presence of two subscribing witnesses.
